[57] CLAIM

The ornamental design for an article holder with belt, as shown.

DESCRIPTION

FIG. 1 is a front perspective view of an article holder with belt showing my new design;

FIG. 2 is a top plan view thereof;

FIG. 3 is a front elevational view thereof;

FIG. 4 is a rear elevational view thereof;

FIG. 5 is a right end elevational view thereof;

FIG. 6 is a left end elevational view thereof;

FIG. 7 is a bottom plan view thereof; and,

FIG. 8 is a cross-sectional view taken along lines 8—8 of FIG. 6.

The dashed lines in FIGS. 1, 3, and 4 represent conventional stitching.
